UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

NORMALLY STATIONARY INERTIA-ACTUATED WEFT DETECTOR.

Application filed July 19, 1926. Serial No. 123,402.

This invention relates to weft detectors for looms and it is the principal object of the invention to provide a detector having a normally stationary weighted part so disposed that the resistance which the same offers to being set in motion can be made use of to apply an indicating force to the detector.

In co-pending application Ser. No. 120,490 filed by Turner there is shown a detector having a regularly moving transerrer arm which presents a detector at periodic intervals to the surface to be detected, the detector being free to move toward detecting position by reason of the energy stored therein. In that application the detector is operative because of the kinetic energy stored in the moving part and it is the principal object of my present invention to apply this same general principle to a detector having a stationary part where the potential energy of a body at rest and the resistance which said body offers to being set in motion is relied upon to provide the force which actuates the detector.

When weft detectors are placed on the magazine side of multi-color weft replenishing mechanisms it is necessary to withdraw the detector on the transferring beat of the loom in order to make clear the path of the incoming bobbin. With a detector depending for its detecting force upon a weighted member normally at rest the latter would offer resistance on the withdrawing stroke which would tend to give the detector an indicating movement and it is a further object of my invention to provide for withdrawing the detector in such a way as will prevent the weighted mass from exerting its normal indicating force on the detector.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a top plan view of my detector showing the same in normal position with the lay approaching front center,

Fig. 2 is a fragmentary view of a portion

of Fig. 1 showing the detector in indicating position,

Fig. 3 is a vertical longitudinal section on line 3—3 of Fig. 1, and

Fig. 4 is a transverse vertical section on line 4—4 of Fig. 1.

Referring to the drawings it will be seen that I have provided a lay 10 having a shuttle box 11 which receives a shuttle S having a bobbin B. A detector stand 12 is secured to any part of the loom as the loom side (not shown) and has a horn 13 provided with a vertical slot 14 which receives the outer end of an actuator lever 15 pivoted at the intermediate portions thereof to a vertically reciprocating block 16. The inner end of the actuator is connected to a rod 17 operatively connected to a weft replenishing mechanism and effective when depressed to initiate replenishment.

A detector is mounted in a bed 18 having a cap 19 secured thereto, the bed being secured in any approved manner to the stand 12. The detector proper is formed of a slide 20 preferably tubular in form and having an upstanding clip 21 through which extends the reduced end of a stud 22. The rear end of said stud has an enlarged threaded head 23 passing through the rear portion of the cap 19 and a compression spring 24 surrounds the stud and lies between the forward wall of the cap and the clip 21, the effect of said spring being to hold the slide 20 yieldingly in rear position. The slide has secured thereto a fixed wedge-shaped yarn penetrating detector 25 which cooperates with a side moving notched or toothed detector 26 pivoted as at 27 to the case 20. The matter thus far described is of common construction and may be as set forth in Patent No. 972,722.

In carrying out my invention I provide the stand 12 with a rearwardly extending arm 30 having an upstanding projection 31 through which extends a stop screw 32. The detector 26 has formed integrally therewith a laterally extending arm 33 terminating in a weighted mass 34 which is positioned for engagement with the stop screw 32.

The detector 26 is provided with a finger 35 which cooperates with the rear right hand end 36 of a controller lever 37 pivoted as at 38 to some part of the bracket or stand

12. A stop screw 39 mounted in the stand 12 engages the lever 37 to limit left hand angular movement thereof. Said lever 37 is provided with a controller end 40 which 5 normally lies to the front of the vertical plane in which the actuator lever 15 moves. The slide 20 has secured thereto a projection 41 through which extends an adjusting positioning screw 42 to cooperate with the 10 end 36 of the controller lever.

The usual depending arms 43 of the transfferer arm are indicated in Fig. 1 and cooperate with a detector withdrawing device comprising a rearwardly extending rod 15 44 slidable in the tubular member and having a lug 45 integral therewith to extend in front of one of said arms. Said rod is guided in the tubular slide 20 as indicated in Fig. 3 and a light compression spring 46 20 is interposed between a portion of the slide and the lug 45 and tends normally to hold the rod 44 in rear position. The arm 33 of the detector 36 is reduced or notched as at 47 in Fig. 4 to form a passage for the rod 25 44, the rear end of the latter being upturned as at 48 (see Figs. 3 and 4) so as to extend behind a portion of the arm 33.

Under normal conditions with sufficient 30 yarn present on the bobbin B the parts will be in the position indicated in Fig. 1, spring 24 moving the slide rearwardly so that the detector 26 is properly positioned with the weight 34 in engagement with the screw 32, the resetting screw 42 having swung the controller 37 to the position indicated in Fig. 1 with the end 40 thereof out of the path of the actuator. As the latter moves forward the detector 25 and the toothed or notched part of detector 26 will be embedded in the yarn of the bobbin so that lateral movement thereof will be prevented as the slide 20 moves forward under influence of the lay and the finger 25 will clear the end 36 of the controller lever.

45 When insufficient yarn for continued weaving is present the wedged detector 35 will engage the bare bobbin before the teeth of the detector 26 have an opportunity to touch the yarn. Inasmuch as there is no 50 yarn to resist angular movement of the detector 26 the latter will be free to move on its pivot 27 as the slide 20 moves forwardly and this action will ensue because of the fact that the weight 34, due to the inertia 55 thereof, will tend to remain unmoved and as the pivot 27 moves forwardly the detector 26 will be swung laterally to the position indicated in Fig. 2. In this latter position the finger 35 will engage and rock 60 the controller lever so that the end 40 thereof will extend under the actuator lever 15. As the latter descends its free movement will be interrupted and rod 17 will be depressed to initiate replenishment as set 65 forth in Patent No. 1,030,748.

Inasmuch as there is no spring associated with the controller lever 37 the latter will remain in the position indicated in Fig. 2 until the resetting screw 42 engages the arm 36 upon the backward stroke of the lay to 70 restore the controller to the normal position indicated in Fig. 1.

On the subsequent transferring pick the arms 43 will be moved forwardly from the position indicated in Fig. 1 to slide the rod 75 44 forwardly against the action of spring 46. This motion will result in engagement by upturned end 48 with arm 43, this engagement taking place between the weight 34 and the pivot about which the latter is 80 movable so that as the detector is withdrawn the pivoted detector will be held against angular motion and a repetition of the indication will be prevented.

From the foregoing it will be seen that I 85 have provided a detector wherein the force tending to give the detector an indicating movement is caused by the resistance which a normally stationary body offers to being 90 set in motion, the latent energy possessed 95 by the weight 34 being relied upon to move the detector 26 angularly. It will also be seen that the detector is withdrawn on transferring beats of the loom by a mechanism which prevents the normal action of weight 34.

Having thus described my invention it will be apparent that changes and modifications may be made therein by those skilled in the art without departing from the spirit 100 and scope of the invention, and I do not wish to be limited to the details herein disclosed but what I claim is:

1. In a weft detector for a loom having a lay movable toward the detector and a 105 surface to be detected, a movable support, a swinging detector, a pivoted connection between the detector and the support, said detector having a portion to engage the surface lying on one side of the pivoted 110 connection, a weighted member movable in a horizontal plane and operatively connected to the swinging detector and having the center of gravity thereof located on that side of the pivoted connection opposite a 115 portion of the surface to be detected, said weighted member being normally at rest and acting by reason of the latent energy stored therein to turn the swinging detector on the pivotal connection as the surface to be detected engages the aforesaid portion during the forward movement of the lay.

2. In a weft detector for a loom having a lay movable toward the detector and a 125 surface to be detected, a movable support, a swinging detector, a pivoted connection between the detector and the support, said detector having a portion to engage the surface lying on one side of the pivoted 130 con-

- nection, a weighted member formed integrally with the swinging detector and movable with the latter in a horizontal plane, said weighted member having the center of gravity thereof on that side of the pivotal connection opposite the aforesaid portion of the swinging detector, said weighted member being normally at rest and tending, by the latent energy stored therewith, 10 to swing said detector in a horizontal plane around the pivotal connection when the surface to be detected engages the aforesaid portion of the swinging detector during the forward movement of the lay.

15 3. In a weft detector for a loom having a lay movable toward the detector and a surface to be detected, a movable support, a swinging detector, a pivoted connection between the detector and the support, said 20 detector having a portion to engage the surface lying on one side of the pivoted connection, a second detector to penetrate the yarn secured to and moving with the support, a weight moving in a horizontal 25 plane and operatively connected to the swinging detector, said swinging detector being limited in movement by the second named detector, said weight having the greater portion of the mass thereof disposed on that side of the pivoted connection 30 opposite the aforesaid portion of the swinging detector and said weighted member being normally at rest so that the latent energy stored therewith tends to move the 35 swinging detector around the pivotal connection away from the second named detector as the surface to be detected engages the aforesaid portion of the swinging detector during the forward movement of the 40 lay.

45 4. In a weft detector for a loom having a lay movable toward the detector and a surface to be detected, a movable support, a swinging detector, a pivoted connection between the detector and the support, said 45 detector having a portion to engage the surface lying on one side of the pivoted

connection, a stop, a weighted member movable in a horizontal plane and operatively connected to the swinging detector and having the center of gravity thereof located on that side of the pivotal connection opposite the aforesaid portion of the swinging detector and yielding means to hold the support in rearward position with the weighted member in contact with said stop, the weight of said member normally being at rest and tending, by latent energy stored therewith, to move the swinging detector about the pivotal connection as the surface to be detected engages the aforesaid portion to move the support normally during the advance movement of the lay against the action of said yielding means. 50

5. In a weft detector for a loom having a lay movable toward the detector and a surface to be detected, a movable support, a swinging detector, a pivoted connection between the detector and the support, said detector having a portion to engage the surface lying on one side of the pivoted connection, a second detector fixed to the support, a weighted member operatively connected to the swinging detector and movable in a horizontal plane and having the center of gravity thereof located on that side of the pivotal connection opposite the aforesaid portion of the swinging detector, said swinging detector normally being limited in movement by the second named detector, 55 yielding means to hold the support in rearward position with the weighted member against the stop, said weighted member, because of the latent energy stored therein, tending to move the swinging detector away from the second detector when the surface being detected engages said member and moves the support forwardly against the yielding means during the forward movement of the lay. 60
